UNITED STATES PATENT OFFICE

THOMAS J. BYRNE, OF TULSA, OKLAHOMA

ICE CAN FILLER

Application filed May 17, 1928. Serial No. 278,441.

My invention relates to ice making machinery and more particularly to ice can fillers.

In the manufacture of ice it is common practice to fill the cans in which the ice is frozen from measuring containers having capacities substantially equal to those of the freezing cans which they are adapted to serve, the freezing cans being usually filled in pairs from a double measuring container; variations in volumes in the filling containers or losses in transfer of water to the freezing cans resulting in corresponding variations in size and weight of the frozen ice blocks.

It is the principal object of my invention to insure uniformity in the ice blocks, and for accomplishing this object I provide an improved form of measuring container and control means for measuring proper volumes in the measuring containers for delivery to the freezing cans.

It is a further object of the invention to provide for adjustment of the measuring containers for different water pressures.

In accomplishing these and other objects of my invention I have provided improved details of structure, the preferred forms of which are illustrated in the accompany drawings, wherein:

Fig. 1 is a detail perspective view of an ice can filler embodying my invention.

Fig. 2 is a vertical sectional view on the line 2—2, Fig. 3.

Fig. 3 is a vertical sectional view on the line 3—3, Fig. 2.

Fig. 4 is a detail perspective view of a valve operating mechanism.

Fig. 5 is a view partly in section of a flexible joint for a valve operating mechanism.

Referring more in detail to the drawings:

1 designates a double measuring container having a bottom wall 2, side walls 3, end walls 4, a solid partition wall 5, perforated reinforcing walls such as 6, and an upper wall 7, the various walls enclosing the separate chambers 8 and 9. The volume of each chamber is equal to a predetermined volume desired in an ice can such as used for containing the water to be frozen into blocks of ice of standard shape and weight.

A continuation of the side walls 3 above

the upper wall 7 and end walls 10 fixed to the upper wall 7 and inset slightly from the end walls 4, define the open chamber 11 for containing surplus water and the valve control mechanism presently described, the upper edges of these walls being provided with an inwardly directed peripheral flange 12.

Mounted on the flanges 12 of the side walls and substantially near an end wall are bearings 13 wherein is mounted a shaft 14 restrained from lateral movement by a thrust collar 15. Pairs of oppositely directed arms 16 and 17 having bifurcated ends 18 are fixed on the shaft in spaced relation, and a like arm 19 is mounted on the shaft outside the wall 3.

Located within the upper wall 7 and aligning with the ends of the paired arms 16 and 17 are ports 20 and openings 21, the ports 20 being provided with seats 20' for semi-spherical valves 22 attached by flexible links 23 to the arms 16. The links 23 include flattened portions 24 received between the bifurcated ends 18 of the arms 16 and pivotally connected thereto by bolts 25. Enlarged cylindrical portions 26 provided with slots 27 and annular reinforcing flanges 28 telescopingly receive the ends of valve stems 29, pins 30 extending transversely through these ends and engageable with the slots 27, connecting the linkage members. It is obvious that with such a connection a flexible linkage member is obtained, a considerable degree of rotary movement of the arm being possible without moving the valve. Guides 31, fastened to, and extending inwardly from the side walls 3, are provided to insure proper alignment of the valves 22 with their respective seats 20'.

Surrounding the openings 21 and fixed to the upper wall 7 are conical guards 32, terminating in cylindrical portions 33, the upper edges of these portions being above the water level of this chamber to prevent the passage of water from the open chamber 11 into the lower chambers 8 and 9 through the openings 21. Linkage members 34 passing through the openings 21 are, except as to length, identical in structure with the links 23, and operatively connect the arms 17 with

outlet valves 35, cooperatively engageable with the seats 36 of outlet fittings 37 secured in the bottom wall 2 for each of the chambers 8 and 9; the outlets being in vertical alignment with the openings 21.

Guides 38 fixed to the side walls 3 retain the outlet valves in proper position relative to their seats. Plug screws 39 screw-threadedly fitted in openings 40 in the end wall 4, provide access to the outlet means.

Pivotedly received between the bifurcated ends of the arm 19 is a bar 41, having stop flanges 42 fixed near its lower end and co-operable with complementary flanges 43 fixed to the outer face of a side wall 3. It will be noted from Fig. 1 that an upward movement of this bar will lower the arms 16 and raise the arms 17, thereby removing the outlet valves 35 from their seats, the control valves 22 remaining closed. Downward movement of the bar will reverse the operations of the valves.

In order to admit water to the measuring chambers and to maintain a determined level in the open chamber after each can-filling operation, I provide a float-actuated control mechanism including an inlet valve housing 44 in the form of a T pipe fitting. The side opening 45 of the fitting extends through 25 and is fixed by welding or the like, to an end wall 10 and screw-threadedly receives an inlet pipe 46 leading from a pump or other source of supply, to which flow is controlled by a valve 47. The lower opening of the 30 housing is provided with an outwardly extending flange 48, to which is attached, as by bolts 49, a disk 50 preferably of soft rubber and mounted between washers 51. The edge of a circular opening 52 in the disk comprises a seat for a spherical inlet valve 53 contained within the housing 44.

Fixed to the upper extremity of the valve is a guide rod 54 adapted for reciprocal movement in an opening 55 of a guide plate 56 secured to a plug screw 57 fitting in the upper opening of the T fitting 44. Secured centrally to the lower extremity of the sphere is a valve stem, having a bifurcated lower end 58 for receiving therebetween one end 50 of an operating lever 59 pivotal on a cross pin 60 extending through the lower end of the valve stem. Paired brackets 61 secured by the bolts 49 to the housing flange 48 are provided with downwardly extending ears 55 sufficiently spaced to receive the operating lever 59, hingedly mounted therebetween on a pin 62 serving as a fulcrum for the lever. The opposite end of the lever 59 is fitted between brackets 63 fixed to the annular wall 64 of a float 65. The upper wall 66 of the float is provided with a filler opening 67 and cap 68. Weights such as 69 may be applied to the float through the filler opening in sufficient quantities to insure the proper operation of the float under different water pres-

sures exerted against the inlet valve 53. A bracket 70 having lateral flanges 71 is fixed to the upper wall 7 for guiding the operating lever 59.

In ordinary practice a can filler of this kind is mounted on suitable supports in an elevated position in the refrigeration plant, the inlet pipe being connected to a source of water supply under pressure. Cranes traveling on horizontal tracks are used for elevating pairs of ice cans and for bringing them in close proximity to the outlet fittings 37, each fitting registering with the open end of an ice can.

Assuming the chambers in the filler to be empty, all the valves being closed and the float resting in lowered position, the valve 47 is opened. Water rushes through the inlet port 52, filling the upper open chamber, the float rising with the water until the predetermined level has been reached, and the valve 53 is closed. Downward movement of the operating bar 41 opens the control valves 22 and water is emptied from the upper chamber into the chambers 8 and 9. Lowering of the float again opens the inlet port and water continues to enter until the lower chambers are filled and the water level in the upper chamber has been reached. Upward movement of the bar 41 then opens the outlet valves 35, the control valves 22 remaining closed, and water flows from the chambers 8 and 9 into a pair of ice cans, the contents of the former being equal to that desired in the latter.

What I claim and desire to secure by Letters Patent is:

1. In an ice can filler, a measuring chamber including upper and lower horizontal walls provided respectively with an inlet and an outlet, and side walls extended above said upper wall to form an auxiliary chamber, said upper wall having a stem receiving aperture, an intake valve housing communicating with the auxiliary chamber, a valve in said chamber subject to pressure of liquid flowing through the housing, a valve controlling said measuring chamber inlet, a valve controlling said outlet having a stem extending through said aperture in the upper horizontal wall, a conical guard for said stem aperture mounted on said wall, common means for actuating the inlet and outlet valves, and intake-valve control means including a float and means for adjusting the weight of the float to the pressure of liquid against said intake valve.

2. In apparatus of the character described, divided measuring chambers, each having an inlet and an outlet opening, a surplus liquid container above said measuring chambers having an inlet for the stream of liquid and communicating with the measuring chambers through said first-named inlets, a shaft extending transversely across the sur-

plus container, arms on said shaft aligning with the first-named inlets and outlets, valves for said inlets and outlets, means for connecting said valves to the arms, and 5 means for rocking the shaft to actuate the valves.

3. In apparatus of the character described, divided measuring chambers, each having an inlet and an outlet opening, a surplus liquid 10 container above said measuring chambers having an inlet for the stream of liquid and communicating with the measuring chambers through said first-named inlets, a shaft extending transversely across the surplus 15 container, oppositely extending arms on said shaft aligning respectively with the first-named inlets and outlets, means for flexibly connecting said valves to the arms, and means for rocking the shaft to actuate the 20 valves.

4. In apparatus of the character described, a measuring chamber including upper and lower horizontal walls provided with an inlet and an outlet, and side walls extended 25 above said upper wall to form an auxiliary chamber, valves controlling said inlet and outlet, an inlet for said auxiliary chamber, the upper horizontal wall having an opening aligning with said outlet, a guard surrounding said opening and projecting above 30 the water level of the auxiliary chamber, a shaft extending transversely across the auxiliary chamber, oppositely extending arms on said shaft aligning respectively with the 35 first-named inlets and outlets including an arm extending through said guard, means for connecting said valves to said arms, and means for rocking the shaft to actuate the valves.

40 In testimony whereof I affix my signature.
THOMAS J. BYRNE.
